UNITED STATES PATENT OFFICE.

GEORGE E. BLAINE, OF DAYTON, OHIO, AND EDWARD HILL, OF CAMBRIDGE CITY, INDIANA, ASSIGNEES TO MILLINGTON KEMPER, TRUSTEE, OF DAYTON, OHIO.

RAILROAD CROSS-TIE AND SLEEPER.

SPECIFICATION forming part of Letters Patent No. 380,274, dated March 27, 1883.

Application filed October 29, 1887. Serial No. 253,751. (No model.)

To all whom it may concern:

Be it known that we, GEORGE E. BLAINE, of Dayton, in the county of Montgomery and State of Ohio, and EDWARD HILL, of Cambridge City, in the county of Wayne and State of Indiana, have invented certain new and useful Improvements in Railroad Cross-Ties and Sleepers; and we do hereby declare that the following is a full, clear, and exact description of the invention, which will enable others skilled in the art to which it appertains to make and use the same, reference being had to the accompanying drawings, and to the letters of reference marked thereon, which form part of this specification.

Our invention relates to that class of cross-ties which are designed as a substitute for the ordinary wooden ties, and has for its object the improvement of such ties by means of which cheapness combined with strength and efficiency are obtained.

The nature of our invention will be fully set forth in the following specification and claims.

In the drawings, Figure 1 is a side elevation of so much of the track and ties as is necessary to illustrate our invention. Fig. 2 is a plan view of the same. Fig. 3 is a transverse section on the line $x-x$, Fig. 1. Fig. 4 is a transverse section of the tie-rod. Fig. 5 is a plan view representing a modified form of anchor-block, and Fig. 6 is a detail perspective view of the tie-rod.

Similar letters of reference indicate similar parts in the respective figures.

The rails A are of the usual or any suitable construction and are spaced and supported by the rods B. These rods B are stamped or cut out of sheet metal, their ends b being enlarged and flat, as shown in Figs. 2 and 6, the central narrow part being bent so as to be of an inverted-U shape in cross-section, as shown in Fig. 4. The flat ends b of the tie-rods rest on wooden blocks C, which in turn rest upon the tops of frusto-conoidal or frusto-pyramidal earthenware or terra-cotta anchor-blocks D, which are buried with their enlarged sides down in the gravel or earth composing the road-bed. These anchor-blocks D are dished

out on the under side, as shown at d', and are also provided with a hole, d, which extends 50 entirely through them. The object of having them hollow is to vitrify and more thoroughly harden them in the process of burning in order to render them more impervious to moisture. The anchor-blocks are also provided with two 55 holes, d' d', through which passes a U-shaped bolt, E. The bolt also passes through the wooden blocks C and the flat ends of the tie-rods B, and receives upon its projecting threaded ends the clip pieces G, which fit over and embrace the flanges of the rail A on each side, and are held down by means of the nuts e, all of which is clearly shown in Fig. 3. Wooden blocks F are interposed between the bolt E and the under side of the anchor-blocks, as 60 shown.

The object of the wooden blocks C and F is to prevent friction between the hard substances of the rails and anchor-blocks, and also to serve as cushions, for, while it is desirable to have all the separate parts firmly secured together, too much rigidity is not desirable.

It will be observed that by making the anchor-blocks frusto-conoidal or frusto-pyramidal and burying them large side down a very secure anchorage is obtained, which will not be affected by the action of moisture or frost; also, by having the under side of the anchor-blocks hollow or dished when the blocks are 75 buried the effect of suction or a vacuum is produced, which tends to hold them more securely in place against any lateral shocks or jars.

While we prefer to use anchor-blocks frusto-conoidal or frusto-pyramidal in shape, yet we 85 do not wish to confine ourselves to these particular shapes, but can use anchors of any form provided their lower ends are made larger than their upper ends, to enable them when buried to resist upward or lateral strain, and 90 we prefer that said anchor-blocks be constructed of earthenware, terra-cotta, or the like, as these substances are extremely cheap and easy to manufacture, and are so light in weight that they can be readily transported in 95 large quantities, and at the same time they are

exceedingly durable and of sufficient strength to resist all strain brought to bear upon them when put to the use intended.

Having thus fully described our invention, 5 what we claim, and desire to secure by Letters Patent of the United States, is—

1. The combination, with the hollow anchor-blocks, of the rails, the tie-rods, the wooden blocks, the clips, and the U-shaped bolts, substantially as described.

2. The tie-rod B, having the enlarged flattened ends b and having its central portion bent to form an inverted-U shape in cross-section, combined with the rails, the anchor-block, the interposed wooden blocks, and securing devices, substantially as specified.

3. As an improved article of manufacture, an anchor-block formed of earthenware, terracotta, or the like, being hollow and having its 20 bottom dished, substantially as described.

4. As an improved article of manufacture, a tie-rod stamped out of a single piece of sheet metal, having its central portion U-shaped in cross section and its opposite ends flattened, 25 enlarged, and having a plane upper surface to pass beneath and support the rails, substantially as described.

5. The combination, with the rails and tie-rods, of anchor-blocks, securing devices to 30 clamp the rails, tie-rods, and anchor-blocks together and in position, cushioning-blocks interposed between the rails and anchor-blocks, and cushioning-blocks interposed between the securing devices and lower surfaces of the 35 anchor-blocks, substantially as described.

6. The combination, with the rails and tie-rods, of anchor-blocks to support the same, U-shaped bolts passing through the anchor-blocks and clamping the rails, tie-rods, and anchor-blocks together and in position, cushioning-blocks interposed between the ends of the tie-rods and upper surfaces of the anchor-blocks, and cushioning-blocks interposed between the lower portions of the U-shaped bolts and the under surfaces of the anchor-blocks, 45 substantially as described.

7. The combination, with the rails and anchor-blocks, of tie-rods connecting the rails, said rods having their central portions U-shaped in cross-section and their ends flattened 50 and enlarged, the enlarged ends supported by the anchor-blocks beneath the rails, and securing devices passing through the ends of the tie-rods and clamping the rails, tie-rods, and anchor-blocks together, substantially as described.

In testimony that we claim the foregoing as our own we affix our signatures in presence of two witnesses.

GEORGE E. BLAINE.
EDWARD HILL.
